STITCH SEPARATING MACHINE

Corwin W. Baker, Hamilton, Mass., assignor to
United Shoe Machinery Corporation, Flemington, N. J., a corporation of New Jersey

Application August 23, 1949, Serial No. 111,873

7 Claims. (Cl. 12—41)

1

This invention relates to stitch separating machines and is herein disclosed as embodied in a machine of the type illustrated and described in United States Letters Patent No. 549,126, granted November 5, 1895, upon the application of John B. Hadaway. In a stitch separating machine of this type the work piece is advanced over a work support by a feed dog which is reciprocated in the path of feed. This feed dog, in its advancing stroke, travels idly over a portion of each stitch and then engages in the interval between two stitches to advance the work piece. As the feed dog engages in the stitch interval, it also separates the stitches and effects a preliminary indentation between them. Upon retraction of the feed dog, an indenting tool is lowered to deepen the indentation in the stitch interval which has just been brought under it by the feed dog. The worktable is yieldingly mounted to accommodate local variations in the thickness of the work piece and is locked against movement during the operation of the stitch indenting tool.

It is an object of the present invention to provide a stitch separating machine of the type under consideration having an improved feeding, stitch separating and stitch indenting mechanism which can be easily adjusted and having also an improved arrangement for supporting and locking the worktable. As shown herein, the various driven members of the illustrated machine are operated by eccentrics, all mounted on a single shaft, each eccentric being connected to a linkage which transmits movement to the operated members. The arrangement of one of these linkages permits the amplitude of feeding movement of the feed dog to be varied without changing the terminal position of its movement. The worktable is supported by a fluid pressure device including a plunger and an air chamber partly filled with liquid. A valve in a conduit between the plunger cylinder and the air chamber can be closed to cause the liquid to provide a rigid support for the worktable. This valve, when open, enables the air pressure to support the worktable resiliently.

These and other features of the invention will appear more fully from the following detailed description when read in connection with the accompanying drawings and will be pointed out in the appended claims.

Referring now to the accompanying drawings, Fig. 1 is a front elevation of an illustrative machine embodying the invention;

Fig. 2 is a side elevation of the machine shown in Fig. 1;

2

Fig. 3 is a sectional view in plan showing the operating instrumentalities of the machine;

Figs. 4, 5, 6, 7 and 8 are vertical sectional views taken on the lines IV—IV, V—V, VI—VI, VII—VII, and VIII—VIII respectively of Fig. 3; and

Fig. 9 is an angular view of the presser feet and the blocks upon which they are mounted.

The work-engaging instrumentalities of the 10 illustrated machine consist of a stitch separating tool and feed dog 20 (Figs. 3 and 6), an indenting tool 22 (Figs. 3 and 5), a pair of presser feet 24 and 26 (Figs. 3 and 9), and a worktable 28 (Figs. 1, 2 and 4). The supporting structure of the 15 machine comprises a column 30 having a base adapted to rest upon the floor. This column supports a post 32 with provision for heightwise adjustment, and mounted upon the post 32 is a head 34 which carries the operating instrumentalities. 20 The various operating instrumentalities of the machine are all driven by eccentrics secured upon a shaft 36 (Fig. 3) journaled in ball bearings 38 which are mounted in the head 34. The shaft 36 may be turned by a handwheel 39; and it is 25 driven by a belt 40 from a motor 42 mounted upon the base portion of the column 30. Counterweights 41 and 43 (Figs. 1 and 3) maintain the shaft 36 in balance.

The several functions of the feed dog 20 are 30 to find the intervals between the stitches, to feed the shoe, to separate the stitches, and to effect a preliminary indentation at each stitch interval. This feed dog 20 is a blade-like member having an orbital movement resulting from components 35 of oscillation in the direction of feed and also heightwise, the feed dog being down in engagement with the work piece during its advance stroke and up out of engagement with the work piece during its retraction.

The heightwise movement of the feed dog 20 is 40 derived from an eccentric 44 (Fig. 6) secured upon the shaft 36 and driving a connecting rod 46 (see also Fig. 3). The free end of the connecting rod 46 is connected by a pin 48 to one 45 end of a toggle link 50, the other end of which toggle link is pivotally secured by a pin 52 to a stationary bracket 54 mounted on the head 34 of the machine. The pin 48 pivotally engages also one end of another toggle link 56 the opposite end of which is pivotally connected by a pin 58 to an ear 59 (Fig. 3) on a bent arm 60 (Fig. 6). This arm 60 is fulcrumed upon a stationary pin 62 which is secured in the head 34. Formed on the arm 60 are a pair of spaced lugs 64 in which 55 is journaled an upright pin 66 secured in a bracket

68. The portion of the bracket 68 which extends between the lugs 64 is held against heightwise movement by those lugs, the bracket being free to pivot about the axis of the pin 66 to enable the feed dog 20, which is carried by the bracket, 5 to oscillate along the line of feed. On the forward end of the bracket 68 is half of an upright guideway 70 (Fig. 3) for the dovetail shank portion of the feed dog 20 and cooperating with the bracket 68 to complete the guideway 70 is a dovetail clamp 71 which can be tightened by means of a clamping screw 72 to hold the feed dog 20 in a desired position of heightwise adjustment. It is evident from the foregoing description that rotation of the shaft 36, by moving the toggle 50, 10 56 toward and from straightened position, will cause the feed dog 20 to be lowered and raised.

Movement of the feed dog 20 back and forth along the path of feed is obtained from an eccentric 74 (Fig. 8) on the shaft 36. A connecting rod 76 driven by the eccentric 74 has its free end pivotally connected by means of a pin 78 to a pair of horizontal toggle links 80 (Fig. 3) and 82. The end of the toggle link 80 which is remote from the pin 78 is pivotally connected by means of a universal ball joint 84 (Fig. 6) to an ear extending laterally from the bracket 68. The end of the toggle link 82 which is remote from the pin 78 is pivotally connected by means of a ball joint 86 (Fig. 3) to a support 88 which, except for purposes of adjustment, is stationary. It is evident that as the shaft 36 rotates, the eccentric 74 will operate through the connecting rod 76 to rock the toggle link 82 about the stationary ball joint 86, and that the resulting motion of the pin 78 will operate through the toggle link 80 to rock the bracket 68 laterally about the pin 66 and thereby to oscillate the feed dog 20 in the path of feed. The feed stroke takes place during the straightening of the toggle, the toggle being so arranged as never to pass dead center. To accommodate the necessary lateral swinging movement of the connecting rod 76, the eccentric 74 is made in the form of a spherical segment, and the engaging strap portion of the connecting rod 76 is made complementally spherical.

Provision for varying the length of the feed stroke of the feed dog 20 is obtained by making the support 88 adjustable. To this end the support 88 is made in the form of a slide which is radially slidable along a guide arm 90 (Fig. 3) secured to an upright pin 92 which is freely rotatable in a stationary bracket 94. The guide arm 90 terminates at its free end in an adjusting handle 95 (Fig. 1). Carried by the guide arm 90 is a spring-pressed friction detent 96 engageable with a stationary sector 98 and having a release handle 100, the purpose of this detent being to hold the arm 90, and therefore the slide 88, in any desired position of angular adjustment about the pin 92. Extending down from the slide 88 and directly below the ball joint 86 is a pin (not shown) which engages an arcuate slot 102 in the bracket 94. As the guide arm 90 is swung about the pin 92, the slide 88 will move radially along the guide arm 90; and the ball joint 86, following the arcuate slot 102, will remain at a fixed distance from the axis of the arcuate slot. Now this axis is so positioned as to include the mid-point of the toggle pin 78 when the connecting rod 76 occupies its most advanced position and when the feed dog 20 has reached the end of its feeding movement. It is evident, therefore, that adjustment of the slide 88 cannot vary the position in which the feed dog ends its feeding stroke, but

that such adjustment will vary the extent to which the toggle 80, 82 is broken by the retraction of the connecting rod 76, and will thus serve to vary the extent to which the feed dog will be retracted by the breaking of the toggle. Suitable stops (not shown) on the sector 98 prevent any excessive adjustment which might cause the toggle to be moved beyond dead center.

Since the individual stitches vary slightly in length, the feed stroke of the feed dog 20 should be adjusted to a length somewhat greater than the maximum length of the stitches of the shoe to be operated upon. As a result of the over-travel thus provided, the feed dog in its retraction will pass beyond the next stitch interval which it is to engage and, in descending, will engage the intermediate portion of a stitch. As the feed dog begins to advance, it will glide idly over the stitch without feeding the shoe and will thus use up the excess portion of its travel. When the feed dog comes to the end of the stitch, it will engage in the stitch interval and, by bearing against the end of the next stitch in advance, it will act as a pawl to feed the shoe to a predetermined position wherein the stitch interval will be at the precise locality for it to be engaged by the indenting tool 22.

The indenting tool 22 is a blade-like member having an orbital movement, approximately elliptical, during which it comes down into engagement with the welt in a forward position inwardly of the sole edge; while in contact with the welt it moves rearwardly toward and, if desired, partially off the sole edge to effect a wiping or burnishing action; it begins to rise before it reaches the sole edge and continues to rise out of contact with the welt; and then, while in its up position, it moves forward inwardly of the sole edge before completing its next descent into operating position. This orbital movement is derived from an eccentric 104 (Fig. 5) on the shaft 36. The indenting tool 22 is mounted on the outer or free end of a connecting rod 106 driven by the eccentric 104. The connecting rod 106, at a point near its outer or free end, is pivotally connected by a pin 108 to an arm 110 which has free swinging movement about a stationary pivot pin 112. The path of orbital movement of the indenting tool 22 can be varied by adjustment of the position 50 of the pivot pin 112 along an arcuate slot 114 formed in the adjacent lateral wall of the head 34, the pin 112 having a reduced threaded end extending through the slot for cooperation with a clamping nut and washer. The axis of the slot 114 coincides with the axis of the pin 108 when the connecting rod 106 is in its most forward position (toward the left as seen in Fig. 5). Adjustment of the pin 112 forward in the slot 114 will flatten the bottom end of the elliptical path 55 of movement of the tool 22 and thus increase the length of operative movement of the tool while in engagement with the welt. Such adjustment is suitable for shoes having wide sole extensions. A reverse adjustment is made for shoes having narrow sole extensions.

The indenting tool 22 has an upwardly extending dovetail shank 116 whereby, with the aid of a dovetail clamp 120 tightened by a clamping screw 124, it can be secured in a guideway formed in a block 118 in a desired position of heightwise adjustment.

The indenting tool 22, as it descends into engagement with the work, must engage in the stitch interval at just the position in which the 75 stitch interval has been left by the advancing feed

dog 20. The indenting tool 22, however, must not interfere with the feed dog 20 as the latter comes to the end of its advancing stroke. In order to avoid such interference, the indenting tool 22 is made laterally yieldable. To this end, the block 118 is pivotally mounted upon a pin 126 which is secured in a block 128 integral with the connecting rod 106, the block 118 being yieldingly urged in a clockwise direction (as seen by the operator) to hold the indenting tool 22 against the presser foot 26. The engaging lateral faces of the indenting tool 22 and the presser foot 26 are inclined to cam the indenting tool to the right as it descends into indenting position, and to permit it to yield to the left as it rises from the work. The means for yieldingly holding the indenting tool against the presser foot consists of a spring-pressed ball detent comprising a ball 130 which is urged into a rounded socket in the block 118 by a spring 132 housed in a bore in the block 128. A screw 134 threaded into said bore provides an adjustable abutment for the spring. The adjacent lateral faces of the indenting tool 22 and the feed dog 20 are complementally inclined to avoid interference as the feed dog rises at the end of its feed stroke.

The presser feet 24 and 26 are spaced apart to enable the feed dog 20 and the indenting tool 22 to operate between them. They function not only as clamps to hold the work stationary during the indenting operation, but their front faces also serve as gages against which the upper of the shoe is held by the operator or, if desired, by a component of cross feed imparted frictionally to the work by the worktable 28 as the worktable rotates idly during each advance of the work. An adjustment for varying the component of cross feed will be described later. The front, or outer, faces of the presser feet are smooth, with rounded edges, to avoid marring the upper of the shoe.

These presser feet 24 and 26 are mounted indirectly upon a swinging bracket 136 (Fig. 9), the main portion of which is integral with and depends from a pair of hubs 138 and 140. The hub 138 is rotatably mounted upon a pin 142, and the hub 140 is rotatably mounted upon a pin 144, these pins being coaxial and serving as trunnion pins about which the bracket 136 can swing freely. The trunnion pin 144 is rigidly secured in a boss 146 which is integral with the machine head 34; and the trunnion pin 142 is mounted in a pair of spaced bosses 148, only one of which is shown in the drawing. For reasons later to be explained, the trunnion pin 142 is made axially slidabile in the bosses 148 and also in the bracket hub 138. Movement of the bracket 136 toward the left is prevented by the engagement of finished end surfaces on the hub 140 and the pin 144; movement toward the right is prevented by the engagement of finished end surfaces on the hub 138 and the adjacent boss 148.

The raising and lowering of the presser feet 24 and 26 are effected by rocking the bracket 136 about its trunnion pins. To this end, the rear portion of the bracket has formed upon it an upstanding lug 150 (see also Fig. 7) which is slotted to form a pair of ears 152. Extending through the ears 152 is a pivot pin 154 which pivotally connects the bracket 136 to one end of a toggle link 156. The opposite end of the link 156 is pivotally connected by a pin 158 to one end of a toggle link 160 which has its opposite end pivotally mounted upon a pin 162. It is evident that forward movement of the toggle pin 158 will

lower the presser feet 24 and 26 into work-clamping position, and that rearward movement of the toggle pin 158 will raise the presser feet.

In order to insure that the work shall be held stationary while the indenting tool 22 is performing its operation, the toggle links 156 and 160 are arranged to pass a little forward of their dead center position as the toggle pin 158 approaches its furthest forward position. This arrangement of the toggle links causes a dwell in the movement of the presser feet 24 and 26 in their down, or clamping, position.

To enable the duration of this dwell to be varied, the pin 162 is adjustably secured in an arcuate slot 164 formed in a bracket 166 which is secured to the adjacent lateral wall of the machine head 34. The pin 162 has a reduced threaded end portion extending through the slot 164 to enable the pin to be clamped in adjusted position by a nut and washer.

The toggle mechanism for rocking the bracket 136 to raise and lower the presser feet 24 and 26 is operated by an eccentric 168 secured on the shaft 36 and driving a connecting rod 170 having its free end pivotally connected to both toggle links 156 and 160 by the pin 158.

In order to avoid substantial change in the down position of the presser feet 24 and 26 when the length of their dwell in down position is varied, the axis of the arcuate slot 164 is so positioned as to coincide with the axis of the toggle pin 158 when the connecting rod 170 occupies its most advanced position (at which time the presser feet will be down). It is evident that, with this arrangement of the slot 164, adjustment of the pin 162 along the slot will not appreciably vary the down position of the presser feet but will vary the extent to which the toggle pin 158 will pass forward beyond its dead center and thus vary the duration of dwell.

The presser foot 24 is mounted in the bracket 136 with provision for both fixed and operating adjustments. It has a shank portion 172 terminating in a dovetail slide which is guided for movement in the direction of feed (i. e., laterally of the machine) by a complementary guideway formed in a block 174. To enable the presser foot 24 to be clamped in adjusted position, the guideway portion of the block 174 is split by a kerf, and the two portions of the guideway thus separated can be drawn together by a screw 176 to bind the dovetail slide. The block 174 has a rearwardly extending shank 178 in the form of a dovetail slide which is guided for forward and rearward movement by a horizontally extending dovetail guideway formed in a block 180. A dovetail clamp 182 cooperates with the block 180 to complete the guideway, and it can be tightened by a screw 184 to clamp the shank 178 in adjusted position. The lower portion of the block 180 has beveled, lateral edges, one of which is indicated in Fig. 9 by the numeral 186, to form a dovetail by which the block 180 is secured to a slide 188. This dovetail on the block 180 engages a complementary dovetail formed by an undercut bevel on the slide 188 and an undercut bevel on a clamp 190. A clamping screw 192 tightens the clamp 190 to bind the dovetail portion of the block 180 to the slide 188 without provision for heightwise adjustment.

Adjustment of the presser foot 24 toward or from the presser foot 26 in accordance with the length of the feed stroke of the feed dog 20 is effected by the same movement of the adjusting handle 95 that varies the length of the feed

stroke. To this end, an undercut guideway 194 (Fig. 9) is formed in the bracket 136 for guiding the slide 188 for free sliding movement in the direction of feed. Integral with the block 180 is an extension 196 having a socket in which an end portion of the slideable trunnion pin 142 is secured by a set screw 198. Secured by a set screw 200 to the trunnion pin 142 and positioned between the spaced bosses 148 is a rearwardly extending arm 202 which is narrower than the space between the bosses to permit axial movement of the trunnion pin. Extending up from the arm 202 is a short pin 204 which is engaged by a radial slot 208 (Fig. 3) formed in a rocker arm 208 extending rearwardly from the rotatable pin 92. It is evident that the swinging of the handle 95 to adjust the feed stroke will serve also to adjust the position of the presser foot 24 in the direction of feed, and that with a long feed stroke the space between the presser feet 24 and 26 will be greater than for a short feed stroke.

The presser foot 26 is mounted in the bracket 136 with provision for fixed adjustments. It has a shank 210 on which is formed a dovetail engaging a complementary dovetail formed in a block 212 and extending in the direction of feed. The dovetail portion of the block 212 is split by a kerf into two parts which can be drawn together by a screw 214 to clamp the presser foot 26 in adjusted position. Extending rearwardly from the block 212 is an integral dovetail shank 216 which engages a complementary dovetail formed in a block 218 and a cooperating clamp 220. The block 218 is integral with the hub 140 and with the bracket 136. The clamp 220 is tightened by a clamping screw 222 to secure the presser foot 26 in a desired position of forward or rearward adjustment.

Heightwise adjustment of the presser feet 24 and 26 has not been found necessary in the illustrated machine. It should be noted, however, that the presser foot 26 is designed with an under face somewhat higher than that of the presser foot 24 to avoid wiping out the impressions that have been formed in the work.

The worktable 28 is mounted indirectly upon a plunger 224 (Fig. 4) which is downwardly yieldable during the feeding of the work and is locked against heightwise movement during each operation of the indenting tool 22, so as to afford a rigid support. The plunger 224 is guided for heightwise movement in a cylindrical bore 226 formed in a stationary block 228 secured to the machine head 34. The bottom of the bore 226 is closed by a plug 229. A stop screw 221, threaded up through the plug 229, engages the bottom of the plunger 224 to prevent excessive accidental depression of the worktable 28. A rod 230, extending parallel to the plunger 224 and movable in unison with the plunger, is guided for heightwise movement in a slot formed in the front face of the block 228 and is retained in the slot by a cover plate 232. The upper end of the rod 230 has a pair of rearwardly extending offset ears in which are formed heightwise slots 236. A clamping screw 238 extending through the slots 236 secures the rod 230 and the plunger 224 in a desired relation of heightwise adjustment. The lower end of the rod 230 extends between a pair of ears formed on a bracket 240 (Fig. 2) secured on the upper end of a treadle rod 242. A screw 244 extending through a heightwise slot 246 in the ears on bracket 240 and also through a bore in the rod 230 adjustably connects the rod to the

10 treadle rod 242. The lower end of the treadle rod is pivotally connected to a treadle 248. A tension spring 250 anchored at its upper end to the stationary cover plate 232 and at its lower end to the bracket 240 normally holds the rod 230 up to a stopped position determined by a pair of pins 252 extending from the rod and engageable with the bottom surface of the block 228. The up or normal position of the worktable 28, when no work piece is in the machine, is determined by the adjustment of the screw 238 in the slot 236. A compression spring 253, interposed between the plug 229 and the plunger 224, assists the spring 250 in holding the worktable 28 up.

20 The worktable 28 is supported by a block 254, the worktable having a depending stem 256 which is freely rotatable in the supporting block. The base of the supporting block 254 is in the form of an arcuate dovetail slide 258 having gear teeth on its lower face and engaging a complementary arcuate guideway formed in a block 260 to provide for tilting adjustment of the worktable about the locality of operation. A pinion engaging the teeth on the slide 258 and having its shaft journaled in the block 260 is provided with a knurled head 262 by which the adjustment can be effected. The worktable 28 and the above-described provision for its adjustment are similar to corresponding features of the machine disclosed in United States Letters Patent No. 1,357,511, granted November 2, 1920, upon the application of Frederick H. Perry.

25 To enable the worktable 28 to be adjusted in the direction of feed, the block 260 has a depending dovetail 264 which is slidable in a guideway formed in a head 266 on the upper end of the plunger 224. This head is split by a kerf and the two portions of the head are drawn together by 30 clamping screws 268 to bind the dovetail 264 in adjusted position. This adjustment enables the component of cross feed, which holds the shoe with the upper pressed in against the ends of the presser feet 24 and 26, to be varied.

35 A hydraulic mechanism is provided for locking the worktable 28 against heightwise movement during the indenting operation. To this end, the space in the bore 226 below the plunger 224 is filled with oil and is connected to a valve chamber 270 by a conduit 272 having, for convenience of assembly, a looped portion 274 extending outside the head 34. The valve chamber 270 has a bore in which is formed an annular port opening 276 which communicates with the conduit 272, the bottom of the bore being open. Connected to the valve chamber 270 somewhat above the port 276 is one end of a pipe 278, the opposite end of which opens into the bottom of a pressure chamber 280 secured to the head 34. The chamber 280 is 40 partly filled with oil, the space above the oil being occupied by air under pressure. Extending up from the top of the chamber 280 (Fig. 1) is an inlet duct 282 fitted with an ordinary tire valve (not shown) and threaded for connection to a tire pump (not shown) by which air under pressure can be introduced into the chamber. The air pressure within the chamber 280 is at all times indicated by a gage 284.

45 Communication between the plunger bore 226 and the interior of the pressure chamber 280 is controlled by a piston valve 286 having upper and lower cylindrical portions which bear against the interior wall of the valve chamber 270 and having also an intermediate portion of reduced diameter 50 to provide an annular passage 288. Into the

upper end of the valve 286 extends a threaded bore whereby the valve is threaded upon a depending stem 290 of a fitting having a pair of upstanding ears 292. A pin 294 pivotally connects the ears 292 to the lower end of a connecting rod 296, the upper end of which is driven by an eccentric 298 on the shaft 36. The valve 286 has a square head 300 depending from its lower end to enable the valve to be turned by a socket wrench and thereby raised or lowered for purpose of adjustment. As shown in Fig. 4, the valve 286 when in its up position closes the port 276 and traps the oil in the plunger bore 226 and the conduit 272, thereby providing a rigid support for the plunger 224. When the valve 286 is in its down position, the port 276 is open and the plunger bore 226 is in communication, through the annular valve passage 288, with the interior of the pressure chamber 280. The air pressure in the chamber 280, acting through the oil, resiliently supports the work against the feed dog 20 during the feed stroke and permits the work to yield downward under pressure of the descending presser feet 24 and 26; and when the presser feet 24 and 26 reach clamping position, the valve 286 is closing to lock the worktable 28.

The springs 250 and 253 are supplemental to the air pressure in the chamber 280 and can be dispensed with if desired.

An attachment for adapting the above-described machine to operation upon unattached outsoles having preattached welts is shown in Fig. 4. It consists of an edge gage 302 overhanging the worktable 28 and connected by a depending shank 304 to an integral block portion 306. Formed in the block portion 306 is an arcuate groove which is slideable over an arcuate tongue 308 extending laterally from a bracket 310, the arc being concentric with the spherical surface of the worktable 28. A clamping screw 312 threaded into the bracket 310 and extending through an arcuate slot in the block portion 306 secures the gage 302 in a desired position of adjustment forward or rearward with respect to the edge of the worktable 28. The bracket 310 is U-shaped to embrace the upstanding portion of the block 254 which is grooved to receive the two arms of the bracket and to guide the bracket for radial adjustment with respect to the worktable 28. Because of the convexity of the working surface of the worktable, such radial adjustment has the effect of varying the height of the gage 302 above the worktable. The arms of the bracket 310 are clamped to the block 254 by screws 314 threaded into the block and extending through slots 316 in the bracket.

The operation of the machine will now be described. To introduce a work piece into the machine, the operator bears down upon the treadle 248; the rapid periodic opening of the valve 286 will thereupon permit the treadle to pull the worktable 28 down so that the operator can insert the marginal portion of the shoe bottom between the worktable 28 and the presser feet 24 and 26. Release of the treadle permits the fluid pressure mechanism, aided by the spring 250 if such a spring is employed, to raise the worktable 28 to its working position. The various operating instrumentalities of the machine will then at once begin to work upon the shoe, regardless of whatever particular phase they may happen to be in.

Suppose, for example, that the valve 286, as shown in Fig. 4, is at the top of its up stroke, holding the worktable 28 momentarily locked

against heightwise movement. The presser feet 24 and 26 will be down in work-clamping position; the indenting tool 22 will be down at about its lowest point to indent the welt; the feed dog 20 will be up out of contact with the work and will be moving in a direction opposite to that in which it feeds the work. As the shaft 36 rotates, in a clockwise direction as seen in Figs. 4 to 8 inclusive, the valve 286 will descend and unlock the worktable 28. The indenting tool 22 will rise up out of the work, and the presser feet 24 and 26 will rise immediately after the indenting tool. The air pressure in the chamber 280, aided by the spring 250, will urge the worktable 28 up with the upper surface of the welt against the presser feet 24 and 26 until the descending feed dog 20 engages the work and holds it down. The feed dog, because of its overtravel, will engage the intermediate portion of a stitch and, as it moves in the direction of feed, will glide idly over the stitch until it engages in a stitch interval, whereupon it will feed the work during the remaining portion of its feed stroke. The feed dog 20 not only separates the stitches but makes a preliminary indentation. At the end of its feed stroke it leaves the stitch interval at the precise point at which the indenting tool 22 will descend. The presser feet 24 and 26 will now begin to descend and, immediately after they are down, the valve 286 will close and lock the worktable with the work clamped against the presser feet. The indenting tool 22, which has been up and laterally out of the way of the feed dog 20, will now descend to deepen the preliminary stitch indentation already formed in the stitch interval. As the indenting tool descends, it will be cammed laterally, by the adjacent inclined face on the presser foot 26 into the precise position for engagement in the stitch interval. This cycle will be repeated indefinitely until the entire portion of the sole margin to be treated has been operated upon, at which time the operator will depress the treadle 248 and withdraw the work from the machine.

Having thus described my invention, what I claim as new and desire to secure by Letters Patent of the United States is:

1. In a stitch separating machine, a feed mechanism comprising a feed dog adapted to enter between the outseam stitches of a shoe and to exert a feeding force upon the shoe, a toggle comprising a pair of links pivoted together at their adjacent ends, the remote end of one link having a pivotal connection to the feed dog, a pivotal support for the remote end of the other link, and means for operating the toggle by varying the angular relation of the links, thereby causing the feed dog to impart a feeding movement to the shoe.

2. In a stitch separating machine having a stitch separating tool and operating means for bringing said tool into and out of a predetermined position of engagement with a work piece, a feed mechanism comprising a reciprocable feed dog adapted to enter between the outseam stitches of a shoe and to exert a feeding force upon the shoe, a toggle comprising a pair of links pivoted together at their adjacent ends, the remote end of one link having a pivotal connection to the feed dog, an adjustable pivotal support for the remote end of the other link, a driven eccentric, a connecting rod between the eccentric and the pivotal connection of the toggle links for operating the toggle and thereby reciprocating the feed

11

dog, a guide for insuring movement of adjustment of said pivotal support in an arcuate path having its center at the point occupied by the pivotal connection of the toggle links when the feed dog is at the end of its feeding stroke, the effect of such adjustment being to vary the length of the feeding stroke of the feed dog and the purpose of said guide being to insure that the feed dog will always occupy the same position at the end of its feed stroke, the lengths of the toggle links and the throw of the eccentric bearing such as to bring said same position into coincidence with the predetermined position in which the stitch separating tool engages the work, and means for securing said pivotal support in adjusted position along said arcuate path.

3. In a machine for operating on shoes, a work-table mounted for heightwise movement, a plunger supporting said worktable, a cylinder in which said plunger is movable up and down, a closed air chamber, and a fluid connection between said cylinder and said air chamber to enable air within the chamber to yieldingly support the plunger.

4. In a machine for operating on shoes, a work-table, mechanism for feeding a work piece step by step over said worktable, means for operating upon the work piece during each interval between feed steps, fluid pressure mechanism for pressing the worktable up, a presser foot engageable with the work piece for limiting the upward movement of the worktable under the influence of said fluid pressure mechanism, a valve in said fluid pressure mechanism for preventing movement of the worktable while in its up position, and means for operating said valve in timed relation to the work feeding steps to enable the worktable to yield down during the work feeding steps and to hold the worktable in up position during each operating interval.

5. In a stitch separating machine, a presser foot, a bracket upon which the presser foot is carried, a support on which the bracket is pivotally mounted for substantially heightwise movement of the presser foot, a pair of toggle links having adjacent ends which are pivotally connected, a pivotal connection between the remote end of one link and the bracket, a pivotal

12

support for the remote end of the other link, said toggle links being so arranged that as they approach dead center they move the presser foot down into clamping position, and means for periodically moving the connected ends of said toggle links through and slightly beyond dead center and then retracting the connected ends, the purpose of the excess movement beyond dead center being to provide a dwell during which the presser foot remains in clamping position.

6. In a stitch separating machine, a feed dog, means for imparting to said feed dog an orbital motion having heightwise and feeding components, a stitch separating tool, and means for 15 imparting to said stitch separating tool an orbital motion which has components that are heightwise and transverse to the direction of feed.

7. In a stitch separating machine, a work-table, a presser foot for clamping a work piece down against the worktable, means for operating said presser foot periodically to clamp and unclamp the work piece, a feed dog, means for imparting to said feed dog an orbital motion having 20 heightwise and feeding components, a stitch separating tool, and means for imparting to said stitch separating tool an orbital motion which has components that are heightwise and transverse to the direction of feed, said operating 25 means and both said motion imparting means being so timed that while the presser foot is up in unclamping position the feed dog is in its down and work-feeding phase and the stitch separating tool is up out of contact with the work piece 30 and while the presser foot is down in clamping position the feed dog is in its up and retracting phase and the stitch separating tool is down and 35 operating upon the work piece.
